UNITED STATES PATENT OFFICE.

CHARLES LEALI, OF KINGSLAND, ARKANSAS.

FENCE-POST.

SPECIFICATION forming part of Letters Patent No. 700,431, dated May 20, 1902.

Application filed December 4, 1901. Serial No. 84,679. (No model.)

To all whom it may concern:

Be it known that I, CHARLES LEALI, a citizen of the United States, residing at Kingsland, in the county of Cleveland and State of Arkansas, have invented certain new and useful Improvements in Fence-Posts, of which the following is a specification.

My invention relates to metal fence-posts for use with barbed or other wire fences, and 10 has for its objects to provide a fence of the class described that will be stronger and more noticeable than ordinary wire fences, reasonable in cost of manufacture, and that has integral with the post means for fastening there- 15 to the line-wires. I attain these objects by the structure hereinafter described, and shown in the drawings, in which—

Figure 1 is a portion of a fence, showing my post in position; Fig. 2, a view in elevation of the post, and Fig. 3 a cross-section through the post.

Referring to the drawings, in which similar reference characters indicate corresponding parts throughout the several views, A represents 25 the post made triangular in cross-section and preferably of Bessemer steel. The lower end of the post is sharpened, as shown at a, to facilitate driving it into the ground.

B represents barbs formed on each of the 30 three corners of the post and are intended to receive the line-wires C of the fence and fastening them by bending the points over the wire. Beginning at the ground the first six barbs are placed six inches apart, while the 35 two upper ones are spaced one foot apart. This spacing of the barbs is to provide for fastening the wires closer together near the ground to fence against small stock. The barbs on one corner only of the post are used

40 at one time, so that when the barbs on one corner of the post are broken another corner of the post may be used and the life of the post prolonged three times what it would be if only one set of barbs were provided. At the 45 same time if the post be made of a fine quality of Bessemer steel the barbs may be bent away from the wires and the same corner of the post used a number of times before its usefulness would be destroyed.

50 In the use of wire fences it is desirable to provide a broad board D above the highest

strand of wire, so that quickly-moving stock, such as horses, may see the fence, and thus avoid injuring themselves by running into the fence. The board D is fastened to the 55 top of the post by means of wire nails driven in and through said board on each side of the corner of the post and through holes E, drilled in the top of the post near each corner, the ends of the nails being bent to hold the board 60 against the corner of the post.

The purpose of making the post triangular in cross-section is to economize the amount of metal necessary to form the post, as well as at the same time make the post of a substantial character, its stability being about 65 equal to a square post having the same width of face, while its weight is a little more than half the weight of such a square post.

The post being made of solid metal it may 70 be readily understood that it affords no harbor for vermin, and if occasionally given a coat of paint or tar its life may be prolonged indefinitely. By having the clips or barbs for fastening the wires integral with the post 75 it may be seen that the expense of providing staples or other means for fastening the wires is dispensed with and that the only tool required in fastening the wires to the post is a hammer to bend the barbs over the wires. 80

The holes E in the top of the post are drilled through the post at each side of each corner of the post on a line parallel with a line drawn from the corner to the opposite side of the triangle perpendicular to said side, the holes 85 at each corner being arranged an inch above or below the holes from either of the other corners to prevent weakening the post by having the holes crossed.

Having thus described my invention, what 90 I claim is—

1. In a fence the combination of a triangular post driven into the ground, having holes drilled through near its top in pairs on lines parallel to lines marking the altitude of the 95 triangle from each side thereof, each pair of holes being drilled on a different plane from the other pairs of holes, barbs formed integral with each edge of the post adapted to be clenched over the line-wires of the fence, and 100 a board fastened to one edge of the post by means of wire nails passing through said

board and holes drilled through the top of said post, substantially as shown and described.

2. In a fence, the combination of a post, 5 triangular in cross-section, driven into the ground and having holes drilled through near its top in pairs on lines perpendicular to the opposite side of said post, each pair of holes being drilled on a different plane from the other 10 pairs of holes, barbs formed integral with each edge of the post to be alternately used to clench the line-wires of the fence, said

barbs being closer together near the base of the post, and a board fastened to one edge of the post by means of wire nails passing through 15 said board and said holes drilled near the top, said nails being clenched against said post, substantially as shown and described.

In testimony whereof I hereto affix my signature in the presence of two witnesses.

CHARLES LEALI.
